Primary Examiner — Amy C Wierenga*Assistant Examiner* — Kathryn Elizabeth Zieno(74) *Attorney, Agent, or Firm* — Gurr Brande & Spendlove, PLLC; Robert A. Gurr(57) **CLAIM**

The ornamental design for a molded coolant hose, as shown and described.

DESCRIPTION

FIG. 1 is a side, bottom perspective view of a molded coolant hose;

FIG. 2 is a left side elevation view of the molded coolant hose;

FIG. 3 is a right side elevation view of the molded coolant hose;

FIG. 4 is a bottom plan view of the molded coolant hose;

FIG. 5 is a top plan view of the molded coolant hose;

FIG. 6 is a rear elevation view of the molded coolant hose; and,

FIG. 7 is a front elevation view of the molded coolant hose.
